UNITED STATES PATENT OFFICE.

EMERY M. HAMILTON, OF NEW YORK, N. Y.

TELEGRAPH-INSTRUMENT.

SPECIFICATION forming part of Letters Patent No. 379,060, dated March 6, 1883.

Application filed April 28, 1886. Serial No. 200,443. (No model.)

To all whom it may concern:

Be it known that I, EMERY M. HAMILTON, of the city, county, and State of New York, and a citizen of the United States, have invented certain Improvements in Telegraph-Relays, of which the following is a full, clear, and exact description, reference being had to the accompanying drawings, forming part of this specification.

My invention relates to telegraph relays, sounders, and other telegraph-instruments in which there is an armature-lever which is adapted to vibrate between stops, and which has a retracting-spring; and my invention consists in the devices and their combinations, hereinafter specified, and as more at length recited in the claims.

Figure 1 is a plan of a relay containing my invention. Fig. 2 is a side elevation of the same. Fig. 3 is a vertical central longitudinal section of the same on the line *xx*, Fig. 1. Fig. 4 is a vertical central section of a modified form, in detail, of one part of my invention. Fig. 5 is a horizontal cross-section on the line *yy*, Fig. 3; and Fig. 6 is a plan of the magnet.

A is the base of the instrument.

B is the magnet.

C is the armature, and C' is the armature-lever fulcrumed at *c*, and thus having the long arm *c'* vibrating between stops, as shown, and the short arm *c''*.

C² is the retracting spring of the armature-lever.

D is a rod or finger-piece, to which the end of the retracting-spring opposite to the end thereof attached to the armature-lever is connected, preferably by an arm, D', which is fixed on said rod and extends therefrom at an angle thereto and reaching to the axis of said spring. The rod D is seated in or supported by a post, E, and is capable of free longitudinal movement therein or thereon in the direction against the tension of the retracting-spring, and is provided with means, substantially as hereinafter set forth, whereby its movement in the opposite direction is adjustably limited.

The post E is preferably hollow, as shown, and the rod D fitted to slide therein as a plunger, with its arm D' extending through a longitudinal slot, *e*, in the post, and with a nut, E', turning on the exteriorly-threaded post,

as shown, and located relatively to the arm D' on the side thereof toward the direction of the tension of the retracting-spring, as shown in Figs. 2 and 3. By means of these devices the rod or finger-piece D has free longitudinal movement in the post in the direction against the tension of the retracting-spring, and its movement in the opposite direction may be adjustably limited by turning the nut E' up or down on the post.

If desired, the rod D may extend entirely through the post, which latter may be screw-seated in the base, as at *a'*, Fig. 4, and the arm D' may reach from the rod beyond the lower end of the post, with a stem, *d'*, reaching up through a suitable slot, *a*, in the base to the connection with the spring, as shown in Fig. 4. The base in this case should be suitably recessed to permit the screw-post to be screwed up or down and to allow for the play of the rod and its arm. The rod D is desirably provided with a button, *d*, on its upper or exposed end, for conveniently applying the pressure of the operator's finger.

My described devices are useful in telegraph-instruments where there are variations in the electric current of the circuit which require that the tension of the retracting-spring of the armature-lever should be quickly and conveniently adjusted to such variations—as, for example, in relays. It is obvious that by pressure upon the rod or finger-piece D by the operator, so as to disengage the same from its motion-limiting device, the tension of the spring C² may be felt wholly through or on the rod, and variations in the current be thus readily detected, and the rod having free movement in the direction against the tension of the spring, it is obvious that the operator may by such pressure on the rod ascertain the proper spring-tension relatively to the current, and by turning the nut E' up or down adjust said spring-tension fixedly to the current.

It is evident that it is possible, in the employment of these described devices, to arrange the magnet with its axis perpendicular to the base, of the instrument, as shown, and consequently with the armature-lever in a substantially horizontal position, and to seat the rod D and its bearing-post E perpendicular to the base, with the arm D' reaching from the rod to the retracting-spring. By this means com-

pactness and economy in the structure of the instrument are secured, and the rod D is so located that while it is pressed upon by the first finger of the operator's left or disengaged 5 hand the nut E' may at the same time be turned up or down by the thumb and second finger of the same hand of the operator, whereby the testing and adjustment of the tension of the retracting-spring may be accomplished quickly and conveniently by one hand 10 of the operator without interfering with his work by the right or other hand, as at the telegraph-key.

F is a bar connecting the poles or cores f of 15 a magnet arranged perpendicular to the base of the instrument. Said bar is located in a recess, a², in the base, and the cores project upward through suitable slots, a³, in the base-plate. A rod, f', seated at one end in the bar 20 F, extends upward through a slot, a⁴, in the base-plate, and passing, preferably, between the cores f and through a hollow pillar, f², there located, as shown, reaches upward through a slot, c⁶, in the armature-lever, where its projected end f³ is threaded, and has a thumb-nut, f⁴, which bears upon the top of the pillar. A spring, f⁵, on the rod has bearing between the bar F and the under side of the base-plate. It is obvious that by means of these devices the 25 turning of the nut f⁴ will operate to raise or lower the magnet on the bar F, and so render the magnet adjustable to the armature perpendicularly to and through the base of the instrument.

G is a pillar fixed in the base and perpendicular thereto and in line with the contact-arm c' of the horizontal armature-lever, the magnet being perpendicular to the base, as described. At the top of the pillar and extended 30 toward and reaching under the end of the arm c' of the armature-lever is the arm or bracket g, in which, extending from below upward, is the adjustable set-screw g', carrying on its upper extended end a contact point or 35 stop, g², immediately in line below the point c³ on the under side of the lever C'. An adjustable set-screw, g³, is seated in the top of the pillar, and projects upwardly therefrom, and has the flanged head g⁴, the rim of which extends 40 over the contact-point c' on the upper side of the armature-lever. By means of this pillar and its described devices, located, as specified, relatively to the perpendicular magnet and horizontal armature-lever, the compactness, 45 economy, and simplicity of the structure of the instrument, as well as complete effectiveness, are secured.

What I claim as my invention, and desire to secure by Letters Patent, is—

60 1. In a telegraph-instrument in which an ar-

mature-lever is vibratory between stops and has a retracting-spring, the combination, with said lever and spring, of a rod connected to said spring, a support in which said rod is seated and in which it has free movement in 65 the direction against the tension of said spring, an arm carried by said rod, and a screw-seated motion-limiting stop in engagement with said arm, whereby the movement of the said rod in the direction of the tension of said spring is 70 adjustably limited, as and for the purpose set forth.

2. In a telegraph-instrument in which an armature-lever is vibratory between stops and has a retracting-spring, the combination, with 75 said lever and spring, of a rod, a hollow and slotted post, in which said rod is fitted to slide, and in which said rod has free movement in the direction against the tension of said spring, an arm carried by said rod and working in said 80 slotted post and connected at its free end to the retracting spring, and a nut working on a thread on the exterior of said post and engaging said arm to adjustably limit the movement of said rod in the direction of the tension of 85 said spring, as and for the purpose specified.

3. In a telegraph-instrument in which an armature-lever is vibratory between stops and has a retracting-spring, the combination, with 90 said lever and spring, of a rod, a hollow externally-threaded post adjustably screw-seated in the recessed base of the instrument, and in which the rod is fitted to slide and have free movement in the direction against the tension of said spring, and beyond the seated end of 95 which said rod extends, together with an arm carried by said rod at its said extended end and in engagement with the end of said post and connected to said retracting-spring, whereby the movement of the rod in the direction of 100 the tension of said spring is adjustably limited, as and for the purpose set forth.

4. In a telegraph-instrument in which the armature-lever is located parallel to the base-plate, as described, the magnet-cores mounted 105 on a bar in a recess in the base of the instrument and extending upwardly perpendicular to the base, toward the armature, through a slot in the base-plate, together with a rod fixed to said bar and extending upwardly, a hollow 110 post with a threaded upper end provided with a nut thereon bearing on said post, and a spring having bearing between said core-bar and the base-plate, as described, and for the purpose set forth.

EMERY M. HAMILTON.
